UNITED STATES PATENT OFFICE.

MICHAEL MORRELL, OF BROOKLYN, NEW YORK, ASSIGNOR, BY MESNE ASSIGNMENTS,
OF ONE-HALF TO GENNARO S. CARLUCCI, OF BROOKLYN, NEW YORK.

AUTOMATIC OIL FEEDER FOR SILK-CONING MACHINE.

Application filed October 28, 1921. Serial No. 511,202.

To all whom it may concern:

Be it known that I, MICHAEL MORRELL, a citizen of the United States, and a resident of the city of New York, borough of Brooklyn, in the county of Kings and State of New York, have invented a new and Improved Automatic Oil Feeder for Silk-Coning Machines, of which the following is a full, clear, and exact description.

10 This invention relates to silk winding machines and particularly to an improved oiling device for machines known as silk coning machines and has for an object to provide a construction which will automatically oil the silk as it passes through the machine.

Another object of the invention is to provide an automatic oiler for oiling silk as it passes through a coning machine in such a manner that an even quantity is supplied 20 to the silk thread throughout its entire length.

A still further object of the invention is to provide an oiling device for oiling the silk thread as it passes through a coning machine, the arrangement being such that an even quantity is supplied to the thread without wasting any of the oil or requiring the attention of an operator.

In the accompanying drawing—

30 Figure 1 is a side view of part of a silk coning machine with an oil feeder embodying the invention applied thereto.

Figure 2 is an enlarged side view of the automatic oil feeder shown in Figure 1 together with certain parts of the coning machine.

Figure 3 is a sectional view through Figure 2 on line 3—3.

Figure 4 is an edge view of part of the structure shown in Figure 2, said view illustrating how the pad is held in place.

Referring to the accompanying drawing by numerals, 1 indicates a coning machine which may be of any desired type and which 45 operates in a well known manner for winding silk thread on to cones. The machine 1 is provided with a member 2 through which the thread 3 passes. Heretofore, an operator would stand near the machine and from time to time discharge oil into a member 2 so that the oil would come in contact with the thread as it passes therethrough. This method oftentimes caused a larger deposit on the thread than desired

at some places while at other places the oil was entirely missing.

In the present invention, the use of an operator for discharging the oil is entirely eliminated. As shown particularly in Figure 2, an oil cup 4 is provided which may be of any desired kind but preferably formed of glass so that the quantity of oil may be observed from time to time. A discharge pipe 5 is connected to the bottom of the cup 4 in any desired manner and the discharge from the cup 4 to the pipe 5 is regulated by a valve member 6 which may be of the needle type or any other desired type. The particular construction of the parts just described may be varied widely provided the pipe 5 extends to a convenient point for discharging onto a pad 7 of felt or other material which will absorb a comparatively large quantity of oil. The pad 7 is supported on the horizontal section 8 of the bar 9 which bar supports the cup 4. A bracket 10 is connected in any suitable manner with the section 8 for receiving the pad 7 and a spring 11 is used for holding the pad against accidental displacement 80 while leaving the edge 12 free. The lower part of this edge is arranged adjacent to a guide 13 which may be of porcelain and held in place by a suitable bolt 14. As shown particularly in Figure 3, the thread 85 3 is held against the face 12 of pad 7 by the guide 13 and, consequently, receives the desired quantity of oil as it rotates against the pad. A plate 15 is carried by the coning machine 1 and is provided with specially prepared slots 16 for receiving the clamping screws 17 whereby the section 8 is clamped firmly in place and yet is permitted an adjustment so that the end of the pipe 5 may be moved forwardly or rearwardly. 95 If desired, pipe 5 could be made to rotate though this ordinarily is not necessary.

What I claim is:—

1. In combination with a silk coning machine, an adjustable bar carried by the coning machine, a pad carried by said adjustable bar and adjustable as the bar is adjusted toward and from the silk as it passes through the coning machine whereby the pressure of the pad against the silk will be varied, a guide for said thread, and automatically controlled means for maintaining said pad saturated with oil. 100 105

2. The combination, with a silk coning machine, of a plate movable horizontally of the machine secured thereto, a frame presenting an upwardly-extending arm and a clamp member adapted to receive an oil pad carried by said plate, said upwardly-extending arm carrying an oil container adapted to automatically feed oil on said pad, and means adjacent one side of said pad for pressing the thread against the pad.
  3. In combination with a silk coning machine, a plate mounting a pad and an oil container, means laterally of said pad adapted to press a moving thread against the pad, said oil container being adapted to keep said pad saturated with oil.
  4. In combination with a silk coning ma-
- chine, a plate presenting a socket adapted to receive an oil-saturated pad, a guide for pressing a moving thread against the pad 20 carried by said socket, an oil container for supplying oil to said pad, and an arm projecting upwardly adapted to support said oil-container.
5. In combination with a silk coning ma- 25 chine, a plate carried by said coning ma- chine movable laterally, means carried by said plate for holding an oil-saturated pad, means for pressing a moving thread from said coning machine against said pad, oil 30 supplying means, and an arm extending up- wardly of said plate adapted to mount said oil supplying means.

MICHAEL MORRELL.
